UNITED STATES PATENT OFFICE.

WILLIAM WAAGBO, OF NORTHPOR, MICHIGAN.

ROTARY ENGINE.

1,317,056.

Specification of Letters Patent. Patented Sept. 23, 1919.

Application filed April 21, 1919. Serial No. 291,441.

To all whom it may concern:

Be it known that I, WILLIAM WAAGBO, a citizen of the United States, residing at Northport, in the county of Leelanau and 5 State of Michigan, have invented new and useful Improvements in Rotary Engines, of which the following is a specification.

One object of my invention is the provision of a rotary engine designed more 10 especially to be actuated by steam, and embodying such a construction and relative arrangement of working parts that it is possessed of high capacity.

Another object of the invention is the 15 provision of an organized mechanism adapted to be used to advantage not only in a rotary steam engine but also in a water force pump, an air pump and an internal combustion engine of the rotary type.

20 Other objects and practical advantages peculiar to my invention will be fully understood from the following description and claims when the same are read in connection with the drawings, accompanying 25 and forming part of this specification, in which:

Figure 1 is a side elevation of the rotary engine constituting the best practical embodiment of my invention that I have as yet 30 devised.

Fig. 2 is a longitudinal vertical section illustrative of the interior construction of the engine.

Fig. 3 is a vertical central section taken 35 at right angles to Figs. 1 and 2.

Figs. 4 and 5 are enlarged detail sections illustrative of the blade mounting.

Fig. 6 is an enlarged perspective of the double ported valve of the engine.

40 Similar numerals of reference designate corresponding parts in all the views of the drawings.

In the present and preferred embodiment of my invention, I employ a support 1 for 45 the exterior casing of the engine, and standards 2 for maintaining in proper position the rotary member of the engine. I also prefer to have the exterior casing of the engine comprise a circular wall 3, and side 50 plates or walls 4, connected in approved manner with the said circular wall.

Arranged as best shown in Fig. 2, relative 55 to the exterior casing, are exhaust chambers 5 which may be connected with a condenser, or with another engine or expansion chamber, in the discretion of the party practis-

ing the invention. Located as best shown in Fig. 2 are groups of cylinders 6. At 7 are conduits connected with the cylinders 6. The ends or heads of the inner cylinder 60 6 are designated by 8, Fig. 3, and at 9 are rings secured to the inner cylinder and forming walls against which annular metal packing members 10 bear as illustrated. At 11, Fig. 3, is a tubular journal for one side 65 of the inner cylinder, and at 12 is the non-rotating shaft complementary to the stationary arms 13 disposed inside of the inner cylinder.

In each of the cylinders 6 is disposed 70 the piston 18 of an exhaust valve 14. It is essential that these valves 14 bear flush in apertures 14^a in the wall 3. Each valve 14 is provided with a stem 15, of angular form in cross-section, disposed in an angular 75 bearing in order to preclude turning of the valve about its axis. Manifestly no packing is required for the said stem.

At 19 is a main supply conduit in communication with a double ported valve 20, the 80 stem of which is numbered 21. At 22 are conduits which are provided for the supply of steam. An exhaust pipe or drain 23 is provided as an adjunct to the said conduits 22.

When steam is let into one of the conduits 22 a portion thereof passes through the conduit 7 and entering the cylinders 6 at one side of the engine, closes and retains in closed position the valves 14 of the pistons 90 16 in said cylinder. At the same time the steam exhausting through the other conduit 22 will create a suction in the other conduit and thereby contribute to the opening of the valves 14 at the other side of the 95 engine, so as to permit the exhaust steam to enter the adjacent exhaust chamber 5.

The ports of the valve 20 are numbered 60, 61, 62 and 63, Figs. 2 and 6. When said valve is in the position shown in Fig. 2, 100 steam entering the port 64 from the supply conduit passes through port 61 to the right-hand conduit 22, Fig. 2, and at the same time exhaust steam from the left-hand conduit 22 passes through the port 62, which 105 extends partly around the valve to the pipe 23. When the valve 20 is turned through half of a revolution to reverse the engine, live steam from conduit 19 will pass from the longitudinal bore 64 in valve 20 through 110 the port 60 to the left-hand conduit 22, and at the same time exhaust steam from the

right-hand conduit 22 will pass through the port 63 to the pipe 23.

By reference to Fig. 3 it will be noted that 24 is a shaft fixed to one of the heads 5 8 of the inner cylinder. Also that 26 are stationary shaft portions, and 27 are the inwardly-reaching arms on the blades 28. The blades 28 form walls of the steam chambers in conjunction with the circular wall 10 8^a of the inner cylinder.

The inner and rotary cylinder comprises spokes 30 fixed to the circular wall 8^a.

There are preferably six of the stationary arms 13, and the spokes 30 are adapted to 15 swing about pins 30^a carried between the arms 13 of the two pairs, Fig. 3.

On their outer and side edges the blades 28 are provided with suitable packing, as indicated by the dotted lines in Fig. 3.

20 In conjunction with the blades 28 I provide metallic packing glands 31, of rocking type, best shown in Figs. 4 and 5, which rocking glands are adapted to slide upon the blades 28 in the direction of the length of 25 said blades. The said rocking glands 31 are held against lateral displacement by the opposed bifurcated portions 31^b of the wall 8^a, which bifurcated portions are possessed of resiliency. Extending through the said 30 bifurcated portions 31^b are bolts 37, equipped with springs 38 for the purpose of taking up wear.

In the practical operation of my novel engine it will be readily understood that the 35 inner cylinder constituting with its appurtenances the piston may be rotated in either direction and may be quickly and easily reversed when necessity demands. The operation of the engine will be attended by the rotation of the inner cylinder including the 40 wall 8^a about the stationary shaft portions 12, and incidental to such rotation of the cylinder, the blades 28 will be rotated or moved about the center afforded by the shaft 45 portions 26.

It will be readily noted that the inner cylinder, the blades, and the parts complementary thereto may be employed in combination and to advantage in a force pump 50 for water or other liquid, an air pump, an internal combustion engine, and analogous apparatus.

I have entered into a detailed description of the construction and relative arrangement 55 of the elements embraced in the present embodiment of my invention, in order to impart a full, clear and exact understanding of the said specific embodiment. I do not desire, however, to be understood as confining myself to the said specific construction 60 and relative arrangement of parts, since in

the future practice of the invention various changes in the form and arrangement may be made as clearly fall within the scope of my appended claims.

65

Having described my invention, what I claim and desire to secure by Letters-Patent, is:

1. The combination of a casing, an inner rotary cylinder having a fixed center of movement, a plurality of blades extending through the cylinder wall and having a center of movement off the first-named center, and rocking glands slidable on the blades and carried in and held against lateral movement by the cylinder; the portions of the cylinder wall at opposite sides of the rocking glands being held under yielding pressure against said glands.

2. The combination of a casing, a revolvable cylinder mounted therein and having a circular wall provided at intervals with gland seats and bifurcated portions at opposite sides of said seats and also provided with means for yieldingly crowding the 85 bifurcated portions inwardly to take up wear, blades having a center of movement off the center of movement of the cylinder and extending through the gland seats, and rocking glands disposed in said seats and 90 slidably receiving the blades.

3. The combination of a cylinder wall having a gland seat and bifurcated portions at opposite sides thereof, and also having means connected with said bifurcated portions to take up wear, a blade extending through the seat, and a rocking gland disposed in the seat and slidably receiving the 95 blade.

4. The combination of a circular casing 100 having ports at intervals in its circular wall, curvilinear chambers at opposite sides of the casing and communicating with said ports, piston cylinders on the outer wall of said chambers, pistons in said cylinders, valves complementary to said ports and connected with said pistons, a conduit connected with the curvilinear chambers, a valve casing connected with said conduit and also with the interior of the circular 105 casing and having a conduit of its own, a control valve in said casing, a rotary cylinder mounted eccentrically in the circular casing and having rocking bearings at intervals in its circular wall, a stationary 110 shaft mounted within the cylinder and off the center thereof and blades mounted to swing about said shaft and slidably arranged in said bearings.

In testimony whereof I affix my signature. 120

WILLIAM WAAGBO.
